BICYCLE CHAIN GUARD

Michael G. Black, 8401 Wheatland,
Sun Valley, Calif. 91352

Filed Feb. 17, 1969, Ser. No. 15,802

Term of patent 14 years

Int. Cl. D12—14

U.S. Cl. D90—5

FIG. 1 is a side elevational view of the bicycle chain guard embodying my new design.

FIG. 2 is a rear elevational view thereof.

FIG. 3 is a sectional view taken on the line 3—3 of FIG. 2.

FIG. 4 is a sectional view taken on the line 4—4 of FIG. 2.

The bicycle, shown in broken lines in FIGURE 1, is included for illustrative purposes only.

I claim:

The ornamental design for a bicycle chain guard, substantially as shown and described.
